US00D921302S

(12) **United States Design Patent** (10) **Patent No.:** **US D921,302 S**
(45) **Date of Patent:** **** Jun. 1, 2021**

(54) **ANIMAL ENCLOSURE**

(71) Applicant: **Dannielle Paraha**, Roxby Downs (AU)

(72) Inventor: **Dannielle Paraha**, Roxby Downs (AU)

(**) Term: **15 Years**

(21) Appl. No.: **29/718,079**

(22) Filed: **Dec. 20, 2019**

(51) LOC (13) Cl. **30-02**

(52) U.S. Cl.

USPC **D30/108**

(57) **CLAIM**

The ornamental design of an animal enclosure, as shown and described.

DESCRIPTION

FIG. 1 is a top, left side perspective view of my new design for an animal enclosure;

FIG. 2 is a front elevational view of the animal enclosure of FIG. 1;

FIG. 3 is a rear elevational view of the animal enclosure of FIG. 1;

FIG. 4 is a side elevational view of the animal enclosure of FIG. 1, the opposite side of the animal enclosure being a mirror image of this figure;

FIG. 5 is a top plan view of the animal enclosure of FIG. 1; and,

FIG. 6 is a bottom plan view of the animal enclosure of FIG. 1.

The broken lines in the above views are for environmental purposes only and form no part of the claimed design invention.

1 Claim, 6 Drawing Sheets
